(57) **CLAIM**

The ornamental design for a nail drill set, as shown and described.

DESCRIPTION

FIG. 1 is a perspective view of a nail drill set showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of the encircled portion labeled, “9” in FIG. 7 thereof;

FIG. 10 is another perspective view thereof;

FIG. 11 is another perspective view thereof;

FIG. 12 is a front elevation view thereof;

FIG. 13 is a back elevation view thereof;

FIG. 14 is a left side elevation view thereof;

FIG. 15 is a right side elevation view thereof;

FIG. 16 is a top plan view thereof;

FIG. 17 is a bottom plan view thereof;

FIG. 18 is an enlarged view of the encircled portion labeled, “18” in FIG. 10 thereof;

FIG. 19 is an enlarged view of the encircled portion labeled, “19” in FIG. 10 thereof;

FIG. 20 is an enlarged view of the encircled portion labeled, “20” in FIG. 11 thereof;

FIG. 21 is an enlarged view of the encircled portion labeled, “21” in FIG. 16 thereof; and,

FIG. 22 is another perspective view of a nail drill set showing my new design, in which the drill is shown inserted through the top of the base.

The dash-dash broken lines in the drawings illustrate portions of the nail drill set that form no part of the claimed design.

(Continued)

The short-dash-long-dash broken lines shown in FIGS. 7, 9, 10, 11, 16, 18, 19, 20 and 21 depict the bounds of the enlarged views and form no part of the claimed design. The nail drill and base are shown separately for clarity of illustration.

1 Claim, 22 Drawing Sheets
